DESIGN FOR A RING BOX

Leo Flier, Chicopee, Mass.

Application April 13, 1938, Serial No. 76,473

Term of patent 3½ years

To all whom it may concern:

Be it known that I, Leo Flier, a citizen of Russia and a resident of Chicopee, county of Hampden, and State of Massachusetts, have invented a new, original, and ornamental Design for a Ring Box, of which the following is a specification, reference being had to the accompanying drawing, forming part thereof, in which

Figure 1 is a perspective view of a ring box illustrating my new design;

Figure 2 is a top plan view of the ring box shown in Figure 1; and

Figure 3 is a transverse central sectional view through the ring box shown in Fig. 2.

The essential features of my design reside in the contour of the side, end and corner portions surrounding the top opening of the box as shown.

I claim:

The ornamental design for a ring box, substantially as shown and described.

LEO FLIER.
